OIL DISPENSER

Gerald L. Ardron, Seattle, Wash., assignor to
 Continental Can Company, Inc., New York,
 N. Y., a corporation of New York

Application June 28, 1939, Serial No. 281,703

15 Claims. (Cl. 226—99)

The invention relates generally to the art of packaging foodstuffs and primarily seeks to provide novel means for filling measured quantities of liquid, such as cottonseed or olive oil, into containers used in the packaging of tuna fish or the like.

In the packaging of tuna fish or the like, it is customary to include in the packaged product a quantity of oil. The oil is delivered into the containers while they are moving along toward the product filling machine or while they are passing from the filling mechanisms toward the closing devices, and it will be obvious that a desirable oil dispensing apparatus of the nature stated must include means for assuring cooperative timing of the dispensing means with the traveling containers, as well as means for accurately controlling the amount of oil to be deposited in each container. It is an object of the present invention to efficiently supply the means stated.

Another object of the invention is to provide a novel oil dispensing apparatus of the character stated in which is included novel means for varying the amount of oil to be deposited in each container.

Another object of the invention is to provide a novel rotor structure, a plurality of valve units movable with the rotor structure and individually engageable with the containers in which the oil is to be deposited and which are actuated by container contact so that no oil will be discharged from a valve unit unless a container is engaged thereby.

Another object of the invention is to provide novel means for feeding oil to the traveling valve units to be dispensed thereby.

With the above and other objects in view that will hereinafter appear, the nature of the invention will be more clearly understood by following the detailed description, the appended claims, and the several views illustrated in the accompanying drawings.

In the drawings:

Figure 1 is a fragmentary vertical cross section illustrating the invention.

Figure 2 is a vertical sectional view taken on the line 2—2 on Figure 1.

Figure 3 is a vertical sectional view taken on the line 3—3 on Figure 1 and illustrates one form of mechanism by which movement may be imparted to the valve rotor.

Figure 4 is a horizontal section taken on the line 4—4 on Figure 1.

Figure 5 is a central vertical section through 55

one of the dispensing valve members looking toward the manifold rotor.

Figure 6 is a fragmentary end elevation illustrating the vertical adjustment of the apparatus and comprising a downward extension of Figure 1 at the line A—A.

In the drawings I have illustrated a feed bed 5 over which containers 6 are fed in suitably spaced relation by the feed dogs 7 projecting upwardly from the feed chain or conveyor 8 which may be driven in any suitable manner (not shown).

A supporting bracket 9 is secured to and extends laterally from the bed, and this bracket includes a depending guide column portion 10 equipped with an adjustable supporting screw 11. The screw forms an adjustable support for the lower end portion 12 of a standard 13 vertically adjustably secured to the bracket 9 through the medium of the slot and screw equipment generally designated 14. The standard carries a drive mechanism housing 15 and includes a bearing for a drive shaft 16 to which rotation is imparted in any suitable manner (not shown) for the purpose of driving the shaft in timed relation with the feed chain 8.

An oil reservoir supporting bracket 17 is removably secured as at 18 upon the housing 15 and includes bearing portions 19 in which are secured laterally projected tie rods 20, the purpose for which will later become apparent. An oil reservoir 21 is removably secured as at 22 upon the bracket 17.

A rotor plate 23 closes the inner face of the housing 15 and is equipped with three bearing hubs 24 which are equidistantly spaced about the center of said plate. Each bearing hub 24 rotatably supports a stub shaft 25, and it will be observed by reference to Figure 1 of the drawings that the stub shafts project from the inner ends of the hubs. Each shaft 25 has a valve member generally designated 26 clamped thereon as at 27, and each valve member includes a depending hollow body portion 28 and an oil delivery duct portion 29, the latter terminating in a bearing hub 30 which is axially aligned with the respective stub shaft 25.

Each duct portion 29 delivers into the interior of the respective valve member which is closed at the top by a ceiling web 31 and at the bottom by a circular valve cup 32 which is preferably threadably mounted on the valve body as at 33 so that it can be removed and replaced at will.

Each removable valve cup 32 is provided with a circular discharge throat 34 which is normally closed by a flanged valve member 35 having a

stem 36 secured thereto as at 37. Each stem projects upwardly from the valve member which it supports and passes through a gland 38 in the respective ceiling web. A spring 39 surrounds each valve stem between the respective ceiling web and valve member 35 and serves to yieldably hold said valve member on its seat so as to normally prevent passage of oil through the respective discharge throat 34. The portion of each valve stem extended above the respective gland 38 is threaded as at 40 and provided with a knurled head 41.

The threaded portion 40 of each valve stem is threadable in a sleeve 42 forming a part of a yoke structure 43 connected at its ends with two plungers 44 slideable in bores 45 formed in the respective valve body 28. Each set of plungers 44 extends a distance below the respective valve discharge throat 34, and each plunger comprising the set carries a container flange engaging foot 46.

At their laterally extended ends, the tie rods 20 carry a bearing bracket 47. A bearing member 48 is removably secured to depend from the bracket 47 and has an oil receiving chamber 49 formed in one end thereof and closed by a removable cap 50 and to which oil is delivered by gravity through a pipe or duct 51 from the reservoir 21, a suitable cutoff valve 52 being connected in said pipe.

A hollow shaft 53 is rotatably supported in the bearing member 48 with an end thereof communicating with the bearing chamber 49. The other end of the hollow shaft projects from the bearing and has a hollow manifold rotor 54 keyed thereon, the inner face of said rotor being closed by a removable cover plate 55 equipped with three bearing bosses 56 axially aligned with the stub shafts 25 and each being adapted to receive one of the valve member bearing hubs 30. Each bearing boss 56 carries a sealing ring 57 for engaging the respective hub 30 and preventing leakage of oil from the manifold rotor, and each sealing ring is secured in place by a removable clamping ring 58.

Any suitable means may be employed for imparting rotation to the rotor plate 23 and for holding the individual stub shafts 25 against rotation about their axes so as to hold the valve units in a perpendicular position during their movement with the rotor plate. The means herein disclosed includes a rotor 59 secured to or forming a part of the plate 23 and equipped with a gear rim portion 60 beyond which each stub shaft 25 extends. The extended end of each stub shaft has a forked crank 61 secured thereon, and the fork of each crank straddles a roller-equipped stud 62 projecting from a gear 63 rotatably supported as at 64 in the housing 15 to rotate about an axis spaced a distance below the axis about which the plate and rotor 23, 59 rotates, as is best illustrated in Figure 3 of the drawings. The gear 63 may be driven by sprocket and chain connections 65 by the shaft 16, and the gears 63 and 60 may be caused to rotate in unison by a pinion sleeve 66 rotatably supported as at 67 in the housing 15.

By reason of the provision of the equipment just above described, rotation imparted to the gear 63 will be transmitted through the pinion sleeve 66 to the rotor and plate 59, 23, and the crank members 61 will be constantly held in perpendicular positions and thereby hold the individual stub shafts 25 against rotation about their individual axes while moving about the axis of the rotor and plate 59, 23. Thus the individual

valve units will always be held in perpendicular position.

As has been previously stated, any suitable means for maintaining the perpendicular positions of the valve units may be employed, and another mechanism suitable for imparting the desired movements to the individual stub shafts 25 is disclosed in U. S. Letters Patent to Warmer & Blood 1,341,487 of May 25, 1920.

In operation, as the individual containers are moved along in spaced relation by the chain 8, either toward a packing machine into which tuna fish or similar products are to be filled into the cans, or from such a packing machine after packing has been accomplished, they will pass beneath and between the rotor elements 23 and 54. The rotor elements are driven in timed relation with the passing containers, and as each container passes beneath and between them, the feet 46 mounted at the lower ends of the plungers 44 of one of the valve units will engage the flange of the container and will be pushed upwardly by the moving container. As the plungers are pushed upwardly the respective valve members 35 will be unseated and oil will pour out of the valve discharge throat 34 into the container as long as the valve member remains unseated. The amount of oil to be filled into individual containers will vary according to the product and the size of the container.

By utilizing the housing position adjusting equipments 11 and 14 the position of the valve units with respect to the feed bed 5 can be altered to accommodate the feeding of cans of different sizes or for simultaneously altering the duration of contact of all of the valve units with the individual containers so as to vary the amount of oil dispensed thereinto.

It will also be obvious that by merely adjusting the knurled heads 41 of the valve stems the positions of the plungers 44 of the respective valve units can be altered so as to alter the duration of contact of the individual units with individual containers.

It is of course to be understood that the details of structure and arrangement of parts may be variously changed and modified without departing from the spirit and scope of my invention.

What I claim is:

1. The combination with a horizontally traveling container feeding conveyor, of a hollow valve member, a rotor continuously rotatable about a horizontal axis for moving said member in the plane of movement of said conveyor, means for feeding oil to the interior of the valve, means carried by the valve member and engageable with containers on said conveyor for releasing oil from the valve member to flow into said containers, and means for vertically adjusting the axis about which said rotor rotates to alter the relation of the conveyor and said valve member to accommodate containers of different sizes or to alter the amount of oil dispensed into each container.

2. In apparatus of the character described, a rotor rotatable about a horizontal axis, a hollow valve member carried by said rotor, means for controlling flow of oil from the valve into receiving containers, a manifold rotor rotatable coaxially with said first named rotor, said valve member being disposed between said rotors, means for supplying oil to the manifold rotor, and means for supplying oil from the manifold rotor to the valve.

3. In apparatus of the character described, a rotor rotatable about a horizontal axis, a hollow valve member carried by said rotor, means for controlling flow of oil from the valve into receiving containers, a manifold rotor rotatable coaxially with said first named rotor, said valve member being disposed between said rotors, means for supplying oil to the manifold rotor, and means for supplying oil from the manifold rotor to the valve, including a connection by which said manifold rotor is caused to move with the first mentioned rotor and the valve. 10

4. In apparatus of the character described, a rotor rotatable about a horizontal axis, a hollow valve member carried by said rotor, means for controlling flow of oil from the valve into receiving containers, a manifold rotor rotatable coaxially with said first named rotor, said valve member being disposed between said rotors, means for supplying oil to the manifold rotor, 15 means for supplying oil from the manifold rotor to the valve, including a connection by which said manifold rotor is caused to move with the first mentioned rotor and the valve, and means for retaining the valve member in a vertical position during its movement with said rotors. 20

5. In apparatus of the character described, a rotor, a hollow valve member carried by said rotor, means for controlling flow of oil from the valve into receiving containers, a manifold rotor, 30 means for supplying oil to the manifold rotor, and means for supplying oil from the manifold rotor to the valve, said last named means including a hollow bearing hub extending from and communicating with the interior of the valve member and extending into and rotatable relative to said manifold rotor. 35

6. In apparatus of the character described, a rotor, a hollow valve member carried by said rotor, means for controlling flow of oil from the valve into receiving containers, a manifold rotor, 40 means for supplying oil to the manifold rotor, and means for supplying oil from the manifold rotor to the valve, said manifold oil supplying means including a hollow shaft to which the manifold rotor is secured and which communicates with the interior of the manifold rotor, a bearing in which said shaft is rotatably supported and having a chamber therein communicating with the interior of the shaft and means 45 for delivering oil to said chamber. 50

7. In apparatus of the character described, a rotor, a hollow valve member carried by said rotor, means for controlling flow of oil from the valve into receiving containers, a manifold rotor, means for supplying oil to the manifold rotor, and means for supplying oil from the manifold rotor to the valve, said last named means including a hollow bearing hub extending from and communicating with the interior of the valve member and extending into and rotatable relative to said manifold rotor, and said manifold oil supplying means including a hollow shaft to which the manifold rotor is secured and which communicates with the interior of the manifold rotor, a bearing in which said shaft is rotatably supported and having a chamber therein communicating with the interior of the shaft and means for delivering oil to said chamber. 55

8. In apparatus of the character described, a rotor, a hollow valve member carried by said rotor, means for controlling flow of oil from the valve into receiving containers, a manifold rotor, 60 means for supplying oil to the manifold rotor, and means for supplying oil from the manifold rotor 65

to the valve, a common support for both said rotors, and means for adjusting said support to vary the position of said valve relative to containers to be filled. 70

9. In apparatus of the character described, a rotor, means for imparting rotation to the rotor, a plurality of stub shafts rotatably mounted in equidistantly spaced relation about the rotor and projecting from one face thereof, means for holding each shaft against rotation about its axis during rotation of said rotor, a manifold rotor rotatably supported in parallel spaced relation to said rotor, a dispensing valve member supported on each shaft, means for causing the manifold rotor to rotate in unison with the first mentioned rotor, and means for delivering liquid to be dispensed to the manifold rotor and from it to each valve member. 75

10. In apparatus of the character described, a rotor, means for imparting rotation to the rotor, a plurality of stub shafts rotatably mounted in equidistantly spaced relation about the rotor and projecting from one face thereof, means for holding each shaft against rotation about its axis during rotation of said rotor, a manifold rotor rotatably supported in parallel spaced relation to said rotor, a dispensing valve member supported on each shaft, means for causing the manifold rotor to rotate in unison with the first mentioned rotor, a hollow shaft on which said manifold rotor is secured and which communicates with the interior of the manifold rotor, a bearing in which said hollow shaft is rotatably supported and having a chamber therein communicating with the interior of the manifold rotor through the hollow shaft, means for supplying liquid to be dispensed to said chamber, and a duct for delivering said liquid from the manifold rotor to each valve member. 80

11. In apparatus of the character described, a rotor, means for imparting rotation to the rotor, a plurality of stub shafts rotatably mounted in equidistantly spaced relation about the rotor and projecting from one face thereof, means for holding each shaft against rotation about its axis during rotation of said rotor, a manifold rotor rotatably supported in parallel spaced relation to said rotor, a dispensing valve member supported on each shaft, means for causing the manifold rotor to rotate in unison with the first mentioned rotor, means for delivering liquid to be dispensed to the manifold rotor and from it to each valve member, each said valve member comprising a hollow body having a discharge opening in its lower portion, a spring seated valve normally closing said opening and having a stem extending from said body, and means adjustably secured to said stem and engageable with containers for unseating said valve and controlling the amount of liquid to be dispensed into said containers. 85

12. In apparatus of the character described, a rotor, means for imparting rotation to the rotor, a plurality of stub shafts rotatably mounted in equidistantly spaced relation about the rotor and projecting from one face thereof, means for holding each shaft against rotation about its axis during rotation of said rotor, a manifold rotor rotatably supported in parallel spaced relation to said rotor, a dispensing valve member supported on each shaft, means for causing the manifold rotor to rotate in unison with the first mentioned rotor, and means for delivering liquid to be dispensed to the manifold rotor and from it to each valve member, each said valve mem- 90

ber comprising a hollow body having a discharge opening in its lower portion, a spring seated valve normally closing said opening and having a stem extending from said body, a plunger member yoke connected with said valve stem and engageable with containers for unseating said valve and causing the dispensing of liquid into said containers, said stem being rotatably and threadably connected with said yoke whereby the position of the plunger can be altered to vary the amount of liquid to be dispensed.

13. The combination with a container feeding conveyor, of a hollow valve member, means for moving said member in an orbital path in the plane of movement of said conveyor, means for feeding oil to the interior of the valve, means carried by the valve member and engageable with containers on said conveyor for releasing oil from the valve member to flow into said containers, and means for individually or collectively adjusting the duration of the engagement of the valve members with the containers to control the amount of oil to be dispensed into the individual containers.

14. The combination with a horizontally travelling container feeding conveyor, of a hollow

valve member, a motor supporting said valve member and continuously rotatable about a horizontal axis for moving said valve member over containers on said conveyor, means for feeding oil to the interior of the valve member, and means carried by the valve member and engageable with containers on said conveyor for releasing oil from the valve member to flow into said containers.

15. The combination with a horizontally travelling container feeding conveyor, of a hollow valve member, a rotor supporting said valve member and continuously rotatable about a horizontal axis for moving said valve member over containers on said conveyor, means for feeding oil to the interior of the valve member, means carried by the valve member and engageable with containers on said conveyor for releasing oil from the valve member to flow into said containers, and means carried by the valve member and engageable with containers on said conveyor for releasing oil from the valve member to flow into said containers, and means for adjusting the position of said valve member carried means to alter the point of engagement thereof with containers on said conveyor thereby to alter the amount of oil to be dispensed into each said container.

25

GERALD L. ARDRON.
